COMBINATION PACKAGE AND SERVING CONTAINER

Emory L. Groff, Jr., Bethesda, Md., assignor to Frank A. Buonauro, Union City, N.J.

Filed Apr. 26, 1961, Ser. No. 64,902

Term of patent 14 years

(Cl. D58—6.5)

FIG. 1.

FIG. 4.

FIG. 2.

FIG. 3.

FIG. 1 is a perspective view of the combination package and serving container showing my new design.

FIG. 2 is a side elevational view thereof with the closure removed.

FIG. 3 is a horizontal cross section taken on the line 3—3 of FIG. 2.

FIG. 4 is a fragmentary bottom plan view thereof, showing the base and lowest outline of the container portion.

I claim:

The ornamental design for a combination package and serving container, substantially as shown.
